(57) **CLAIM**

The ornamental design for a device for moving heavy appliances, as shown and described.

DESCRIPTION

FIG. 1 is a perspective view of the device;

FIG. 2 is a side view thereof;

FIG. 3 is a top view thereof;

FIG. 4 is a bottom view thereof;

FIG. 5 is a front view thereof; and,

FIG. 6 is a side view thereof, showing the device in the context of an environmental structure.

The broken line portions of FIG. 6 are included for the purpose of illustrating environmental structure and form no part of the claimed design.
